CLAIM

I claim the ornamental design for a "tote bag", as shown and described.

DESCRIPTION

FIG. 1 is a perspective view of the tote bag;

FIG. 2 is a front view thereof;

FIG. 3 is a back view thereof;

FIG. 4 is a left side view thereof;

FIG. 5 is a right side view thereof; and,

FIG. 6 is a top view thereof.

The broken lines in the drawings depicted portions of the tote bag that form no part of the claimed design.
